UNITED STATES PATENT OFFICE.

CHARLES A. JOSLIN, OF NORTH ATTLEBORO, MASSACHUSETTS.

DESIGN FOR A CARVING FORK OR SIMILAR ARTICLE.

Application filed May 4, 1929. Serial No. 31,095. Term of patent 3½ years.

To all whom it may concern:

Be it known that I, CHARLES A. JOSLIN, a citizen of the United States, residing at North Attleboro, in the county of Bristol and State of Massachusetts, have invented a new, original, and ornamental Design for a Carving Fork or Similar Article, of which the following is a specification, reference being had to the accompanying drawings, forming part hereof.

Fig. 1 of the drawings is a plan view of the fork showing the ornamental handle.

Fig. 2 is an end view thereof illustrating the cross sectional contour thereof.

I claim:

The ornamental design for a carving fork or similar article as shown.

CHARLES A. JOSLIN.
